(57)

CLAIM

The ornamental design for a mixing tool substantially as shown and described.

DESCRIPTION

FIG. 1 is a front elevation view of a mixing tool embodying my new design;

FIG. 2 is a rear elevation view thereof;

FIG. 3 is a top perspective view thereof;

FIG. 4 is a top plan view thereof;

FIG. 5 is a bottom plan view thereof;

FIG. 6 is a bottom and front perspective view thereof; and,

FIG. 7 is a bottom and rear perspective view thereof.

The broken lines in the drawings illustrate portions of the mixing tool that form no part of the claimed design.

1 Claim, 6 Drawing Sheets
